Primary Examiner — Manpreet Matharu*Assistant Examiner* — Aula Soroush(74) Attorney, Agent, or Firm — Banner & Witcoff, Ltd.(57) CLAIM

The ornamental design for a shirt, as shown and described.

DESCRIPTION

FIG. 1 is a front left perspective view of a first embodiment of a shirt showing our new design;

FIG. 2 is a front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is bottom view thereof.

The dashed-dot lines adjacent to the shaded areas illustrate a boundary of the claim and form no part of the claimed design.

In the drawings, the randomly spaced stippling is shown merely for the purpose of illustrating surface shading and does not represent any particular color, material, texture or finish.
